UNITED STATES PATENT OFFICE.

HAMILTON DUDLEY COLEMAN, OF BILOXI, MISSISSIPPI.

ENVELOPE.

Application filed October 8, 1923. Serial No. 667,945.

To all whom it may concern:

Be it known that I, HAMILTON DUDLEY COLEMAN, a citizen of the United States, residing at Biloxi, in the county of Harrison and State of Mississippi, have invented certain new and useful Improvements Relating to Envelopes; and I do hereby declare the following to be a full, clear, and exact description of the invention, such as will enable others skilled in the art to which it appertains to make and use the same.

The present invention relates to envelopes or the like for enclosing letters and other matter adapted to be transported through the mails.

An object of the present invention is to provide a structure of envelope which may be easily and economically produced from a single blank of substantially rectangular form and which requires but few operations, and a blank which may be used as an envelope for enclosing a letter sheet, or which may be written directly upon to provide the letter sheet itself.

Another object of the invention is to provide an envelope of this character which may be quickly and easily sealed and which may be easily mutilated when being opened to gain access to the interior of the envelope and which is provided with a closing sheet adapted to be used in connection with a body part of the mutilated envelope for return use of the device.

With the foregoing and other objects in view, the invention will be more fully described hereinafter, and will be more particularly pointed out in the claim appended hereto.

In the drawings, wherein like symbols refer to like or corresponding parts throughout the several views.

Figure 1 is a front elevation of the envelope constructed according to the present invention and being sealed.

Figure 2 is a longitudinal section taken through the same substantially on the line 2-2 of Figure 1.

Figure 3 is a plan view of the blank from which the envelope is made, and showing the normal position of the device when it is open and ready for use.

Figure 4 is a perspective view of a supplemental closure sheet adapted for use with the envelope, and

Figure 5 is a rear face view of the closure

sheet having the marginal flaps thereof folded over.

Referring to the drawing 10 designates the front wall of an envelope which is preferably integral with the back wall 11. The front and back walls 10 and 11 are of substantially the same dimensions and are foldable one upon the other on a crease line 12. The blank providing the front and rear walls 10 and 11 has longitudinal lines of perforation 13 which are placed inwardly from the longitudinal edges of the blank and extend throughout the entire length of the blank, and the blank is also provided with transverse lines of perforations 14 spaced inwardly from the opposite ends of the blank. These lines 13 and 14 of perforations form marginal edge flaps which extend entirely about the blank. The marginal flaps about the three exposed edges 75 of the back wall 11 have a coating of an adhesive, as shown in Figure 3, and are adapted to be secured by the adhesive to the corresponding flaps of the front wall when the latter is folded over on the line 12 to 80 thus seal the envelope at its open edges.

The front wall 10 is adapted upon its face to bear the address of the party to whom the envelope is to be sent, and also adapted to carry the usual postage stamp 15 which may 85 be secured thereon by an adhesive, or which may be impressed and printed directly upon the paper or other material of which the envelope is made.

A letter sheet or other device may be 90 placed between the walls 10 and 11 and the latter sealed together at their marginal portions by moistening the adhesive layer on the flaps of the back wall 11. When sealed the envelope is closed at its marginal edges 95 as shown in the sectional view in Figure 2, when it is desired to gain access to the contents of the envelope the adhering marginal flaps are torn off along the lines 13 and 14 of perforations so that the walls 10 and 11 100 may be open or swung one upon the other so as to remove the contents of the envelope.

After the envelope has been used, and it is desired to again use it, or the major portion thereof, for remailing, a sealing sheet 16 may be used such as shown in Figures 4 and 5. The sheet 16 is substantially of the same dimension as the back wall 11 of the envelope and has longitudinal and lateral lines 17 and 18 of perforations 110

at its top and bottom edges and at one end edge to define separable edge flaps about the sealing sheet. The other end of the sheet 16 is provided with a larger flap 19 which may be used as the closure flap of the envelope. As shown in Figure 5, the front and rear walls 10 and 11 of the envelope may be folded together and enclose a letter sheet and then placed against the rear face of the sealing sheet 16 and the marginal flaps of the latter turned over the edges of the walls 10 and 11 and secured by an adhesive to the rear face of the rear wall 11.

15 For this purpose the marginal flaps of the sealing sheet 16 may be provided with a coating of suitable adhesive as shown in Figure 4. If desired the smaller flaps of the sealing sheet may first be turned over 20 and gummed in place and the larger flap 19 left open until the matter to be mailed is introduced into the newly formed enclosure.

25 The flap 19 may then be secured over the rear wall 11 to seal the contents within the enclosure. It is apparent that the sealing sheet 16 may be used in connection with one or more of the walls of the envelope and that it provides a new surface on its front 30 face for an address of a person to receive the package and that it also may receive a stamp 15 by either separate application or direct impression and printing.

It is obvious that various changes and

modifications may be made in the details of 35 construction and design of the above specifically described embodiment of this invention without departing from the spirit thereof, such changes and modifications being restricted only by the scope of the 40 following claim.

What is claimed is:—

A mailing device including a wrapper and an envelope, said envelope comprising a rectangular blank provided with a row of 45 perforations extending completely around the same adjacent to its perimeter, a portion of the blank lying between the perforations and the perimeter being coated with adhesive, said blank being folded on a medial 50 line with its corresponding edges and perforations in coincidence whereby the marginal portions of the envelope may be severed therefrom by rupturing the envelope along the superposed lines of perforations, 55 said wrapper comprising a sheet corresponding to but larger than the mutilated envelope and having a flap, and a marginal strip of adhesive separated from the body 60 of the sheet by a line of perforations, said wrapper adapted to receive the mutilated envelope with said adhesive-coated marginal portions folded over the edges thereof and secured to the exposed face of the envelope 65 whereby to seal the longitudinal edges, and said flap similarly folded to seal the end of the envelope.

HAMILTON DUDLEY COLEMAN.
